UNITED STATES PATENT OFFICE

CHARLES B. OULTON, OF ATTLEBORO, MASSACHUSETTS, ASSIGNOR TO NIFTICRAFT
MOULDING WORKS, INC., A CORPORATION OF RHODE ISLAND

DESIGN FOR A BRACELET

Application filed October 28, 1931. Serial No. 41,555. Term of patent 7 years.

To all whom it may concern:

Be it known that I, CHARLES B. OULTON, a citizen of the United States, residing at Attleboro, in the county of Bristol and State of Massachusetts, have invented a new, original, and ornamental Design for a Bracelet, of which the following is a specification, reference being had to the accompanying drawings, forming a part thereof, in which

Figures 1 and 2 are front and side views respectively of a bracelet showing my new design, and Figure 3, a section of the same on line 3—3 of Figure 1.

I claim:—

The ornamental design for a bracelet substantially as shown.

CHARLES B. OULTON.
